[57] CLAIM

The ornamental design for a support bar for fishing lures and jigs, as shown and described.

DESCRIPTION

FIG. 1 is a perspective view of a support bar for fishing lures and jigs showing my new design, broken away to indicate indeterminate length and the fishing lure being shown in broken lines for illustrative purposes only; FIG. 2 is an enlarged fragmentary top view thereof; FIG. 3 is an enlarged fragmentary side view thereof; FIG. 4 is an enlarged fragmentary bottom view thereof; FIG. 5 is a sectional view taken in the direction of the arrows on line 5—5 of FIG. 2; FIG. 6 is a sectional view taken in the direction of the arrows on line 6—6 of FIG. 2.
